Primary Examiner — Robert Delehanty**CLAIM**

I claim the ornamental design for urine-splatters preventing inverted flushable funnels and their storage box, as shown and described.

DESCRIPTION

The application claims the benefits of U.S. application Ser. No. 12/544,913 filed 20 Aug. 2009, PCT Application No. PCT/US2010/22008 filed 25 Jan. 2010, and U.S. application Ser. No. 13/368,208 filed 7 Feb. 2012.

FIG. 1 is a perspective view of the inverted flushable funnel having flaps at top open end to be held by human hands, when urinating in a commode from standing position;

FIG. 2 is a perspective view of a stack of the flushable funnels; FIG. 3 is a perspective view of the storage box with opened cap;

FIG. 4 is a perspective view of a stack of flushable funnels placed in the storage box; and,

FIG. 5 is a perspective view of the storage box hanged on water tank of the commode.

The broken lines depicting a commode in FIG. 5 are for illustrative purposes only and form no part of the claimed design.
